DRAFTSMAN'S TRIANGLE HAVING A
PARALLEL LINE SPACER

Leonard G. Peretti, Chicago, Ill.

Application October 19, 1951, Serial No. 252,158

1 Claim. (Cl. 33—110)

1

This invention relates to drafting instruments. More particularly, the invention has reference to a draftsman's triangle, so constructed as to have embodied therein a parallel line spacing means.

In drafting operations, or for that matter in many other types of drawing, the necessity of making a series of equidistantly spaced parallel lines frequently arises. In this connection, measuring off of the distance between each pair of adjacent parallel lines is a laborious and time-consuming operation, and is avoided wherever possible. On the other hand, visual determination of the spaces between adjacent parallel lines to be drawn results in inaccuracies.

Accordingly, it is the main object of the present invention to provide a draftsman's triangle having a parallel line spacing means embodied therein, said means being so formed as to permit a series of parallel lines to be drawn, in a minimum time and with maximum facility.

Another important object is to provide a drafting instrument of the character described which has a parallel line spacer incorporated therein in such a manner that the spacer will not interfere with ordinary use of the instrument.

Still another important object is to provide a draftsman's triangle as stated wherein the parallel line spacing means is so designed as to be capable of incorporation in the triangle at a minimum of cost.

Yet another important object is to provide a draftsman's triangle as described wherein the parallel line spacing means is adjustable to predetermine, within wide limits, the distance which is to occur between the several parallel lines.

Other objects will appear from the following description, the claims appended thereto, and from the annexed drawing, in which like reference characters designate like parts throughout the several views, and wherein:

Figure 1 is a plan view of a drafting board, showing the draftsman's triangle formed in accordance with the present invention, as it appears when in use;

Figure 2 is an enlarged plan view of the triangle;

Figure 3 is a fragmentary perspective view of the triangle and of the parallel line spacing means embodied therein;

Figure 4 is a longitudinal sectional view through the spacing means, on a scale enlarged still further, taken substantially on line 4—4 of Figure 2; and

Figure 5 is a transverse sectional view through the spacing means, taken on line 5—5 of Figure 2 and drawn on the scale of Figure 4.

2

The draftsman's triangle formed in accordance with the present invention has been generally designated 10, and is formed with a rectangular opening 12 having perpendicularly related sides that are parallel to the respective perpendicularly related legs of the triangle.

Formed upon and extending from end to end of opposite sides of the opening 12 are tongues 14, disposed medially between the top and bottom faces of the triangular body 10, as may be readily noted from Figure 4.

The tongues 14 provide guides for slidable movement of a flat plate 16 adapted to be shifted longitudinally of the rectangular opening 12.

15 The plate 16 is formed to a thickness corresponding to that of the triangular body 10, and as may be noted from Figure 5, the plate 16 is integrally formed with outwardly extended longitudinal tongues 18, said tongues 18 being contiguous to the bottom face of the plate 16 and underlying the guide tongues 14 of the triangular body 10.

At its opposite sides, the rectangular plate 16 is formed with longitudinal recesses 20, contiguous to the top face thereof, said recesses being adapted to receive filler pieces 22, that are bonded along opposite sides to the walls of the recesses. The filler pieces project beyond the recesses, to an extent corresponding to the projection of the tongues 18 (Figure 5). Thus, there are defined within opposite sides of the rectangular plate 16 guide grooves receiving the guide tongues 14.

35 The plate 16 is freely slidable upon the guide tongues 14, sliding from end to end of the opening 12.

Formed in the rectangular plate 16, and disposed medially between the opposite sides of the plate, is a longitudinal slot 24, closed at opposite ends, said slot receiving a vertically positioned stem 26. The stem 26 (Figures 4 and 5) is threaded at its upper end, said upper end projecting beyond the top face of the rectangular plate 16 and being threadedly engaged with a knob 28.

40 At its lower end, the stem 26 is provided with an enlargement 30 embedded in an extension member 32, that is recessed in a complementarily formed seat 34, that is provided in the bottom face of the plate 16.

The extension member 32 is slidable relative to the rectangular plate 16, and is provided with a series of graduations 36, said graduations in the present instance being inches and fractions thereof.

55 The extension member 32 is adjusted so as to

project beyond the rectangular plate 16 a selected distance, the end wall of the rectangular plate being brought into register with a selected graduation. This causes the spacer unit, said unit comprising the plate 16 and the extension member 32, to be extended as to the overall length thereof, to bring its length up to a predetermined ratio relative to the length of the opening 12 in which said unit is slidably mounted. In other words, the overall length of the spacer unit, when subtracted from the length of the opening 12, will give the space which is to occur between each pair of parallel lines to be drawn.

In Figure 1, I have illustrated a T square 38, that is applied to a conventional drafting board 40 on which a sheet of drafting paper 42 is provided. Parallel lines 44 are to be drawn on the sheet of paper.

The triangle is applied to the T square straight edge in the usual manner, after the spacer unit has been adjusted to a selected length. The triangle is held against the board, and one line 44 is drawn.

The spacer unit is then held against movement, and the triangle is shifted along the straight edge relative to the now stationary spacer unit, until the free end of the extension member is engaged by the adjacent end of the opening 12, in the manner shown at the right in Figure 1.

A second line 44 is now drawn, after which the triangle is held stationary while the spacer unit is moved until it again abuts against the opposite end of the opening 12. The unit is then held stationary once again, and the triangle shifted to the limit allowed by the spacer unit. Another line is drawn, and succeeding lines are drawn in the same manner.

It will be readily apparent that with considerable ease, one can acquire dexterity in the manipulation of the device, so as to make the relative movements between the triangular body 10 and the spacer unit unconsciously during the drawing of a series of parallel lines.

It is also believed worthwhile to note that the device is one which does not interfere with ordinary use of the triangle, since it does not project beyond any side of the triangle, or below the bottom face of the triangle.

Still further, the device is capable of incorporation in triangles without increasing the cost thereof materially, the increased cost being more than offset by the benefits to be obtained through use of the device.

It is believed clear that the invention is not necessarily confined to the specific use or uses thereof described above, since it may be utilized for any purpose to which it may be suited. Nor is the invention to be necessarily limited to the specific construction illustrated and described, since such construction is only intended to be illustrative of the principles of operation and the means presently devised to carry out said principles, it being considered that the invention comprehends any minor changes in construction that may be permitted within the scope of the appended claim.

What is claimed is:

A drafting instrument comprising a draftsman's triangle having a rectangular opening

formed with perpendicularly related sides respectively parallel to the perpendicularly related sides of said triangle, said opening having guide tongues extending the length thereof, along the opposite side edges of the opening; a rectangular plate mounted in the opening and having its top and bottom surfaces flush with the top and bottom surfaces of the triangle, said plate having a wide, shallow recess formed in its underside, said recess extending the length of the plate, the plate having longitudinal recesses of right angled cross section opening on one of said surfaces thereof and extending along the opposite sides of the plates; filler pieces fixedly mounted in the second-named recesses; longitudinal guide tongue members integral with the respective sides of the plate contiguous to the other surface of the plate, the filler pieces and the tongue members of the plate projecting outwardly from the plate to the same extend and being spaced apart to define guide grooves at opposite sides of the plate slidably interengaged with the guide tongues; a graduated extension member disposed within said recess, said extension member having a bottom surface flush with the bottom surface of the rectangular plate, one end of the extension member projecting beyond one end of the plate; and means engaging the plate and extension member against relative movement from selected positions to which the extension member is slidably adjusted relative to the plate, said means comprising a stem projecting upwardly from the extension member and embedded in the extension member, said plate having an elongated, closed slot through which the stem is extended, said means further including a knob threadedly engaged with the stem for tightening of said knob against the upper surface of the plate, thereby to rigidly interengage the plate and extension member in said selected positions of adjustment of the extension member, said plate and extension member constituting a spacer unit slidable from end to end of the rectangular opening of the triangle and adjustable as to its overall length, the difference between the overall length of the spacer unit and the length of the triangle opening determining the distance the triangle may be moved relative to the spacer unit, thus to permit the drawing of a series of parallel, equidistant, straight lines first by moving the triangle while the spacer unit is held stationary, and then by moving the spacer unit while the triangle is held stationary.
